(57) **CLAIM**

The ornamental design for a computer display with animated graphical user interface showing video reviewer flags, as shown and described.

DESCRIPTION

FIG. 1 is a front view of a computer display with animated graphical user interface showing video reviewer flags showing the first image in a sequence according to a first embodiment;

FIG. 2 is a second image thereof;

FIG. 3 is a third image thereof;

FIG. 4 is a fourth image thereof;

FIG. 5 is a fifth image thereof;

FIG. 6 is a front view of a computer display with animated graphical user interface showing video reviewer flags showing the first image in a sequence according to a second embodiment;

FIG. 7 is second image thereof;

FIG. 8 is a third image thereof;

FIG. 9 is a fourth image thereof; and,

FIG. 10 is a fifth image thereof.

In each figure, the dot-dash broken lines illustrate computer display portions and the dash-dash broken lines illustrate portions of the graphical user interface. The dot-dash broken lines and the dash-dash broken lines illustrate the environment of the claimed design but form no part of the claimed design.

The appearance of the animated graphical user interface sequentially transitions between the images shown in FIGS. 1-5 and between the images shown in FIGS. 6-10. The process or period in which one image transitions to another image forms no part of the claimed design.

1 Claim, 10 Drawing Sheets
